UNITED STATES PATENT OFFICE.

RICHARD R. DEFFERT, OF MANVILLE, NEW JERSEY.

CONTROLLING-VALVE FOR STEAM-TURBINES.

1,173,180.

Specification of Letters Patent. Patented Feb. 29, 1916.

Application filed May 15, 1915. Serial No. 28,262.

To all whom it may concern:

Be it known that I, RICHARD R. DEFFERT, a citizen of the United States, and residing at Manville, in the county of Somerset and State of New Jersey, have invented certain new and useful Improvements in Controlling-Valves for Steam-Turbines, of which the following is a specification, such as will enable those skilled in the art to which it appertains to make and use the same.

This invention relates to steam turbine engines, and particularly to means for controlling the operation of engines of this class, and the object thereof is to provide a device or apparatus of this class which is simple in construction, uniform in operation and automatically controlled by the load on or applied to the engine; and with this and other objects in view the invention consists in a device or apparatus of the class specified, constructed and operated as hereinafter described and claimed.

The invention is fully disclosed in the following specification, of which the accompanying drawings form a part, in which the separate parts of my improvement are designated by suitable reference characters in each of the views, and in which:

Figure 1 is a section on the line 1—1 of Fig. 2; Fig. 2 a section on the line 2—2 of Fig. 1; Fig. 3 a sectional and diagrammatic view of the complete device or apparatus made according to my invention; Fig. 4 a view on an enlarged scale of a part of the construction shown in Fig. 3, and showing the separate parts of said construction in a different position; Fig. 5 a side view looking in the direction of the arrow 5 of Fig. 1 but omitting part of the construction shown in Fig. 1; Fig. 6 a transverse section on the line 6—6 of Fig. 5 and on the line 6—6 of Fig. 1; Fig. 7 a section on the line 7—7 of Fig. 8; Fig. 8 a section on the line 8—8 of Fig. 7; and, Fig. 9 a side view of a detail of the construction shown in Figs. 7 and 8.

In the accompanying drawings, I have shown at *a* the main steam supply pipe of a steam driven turbine, said pipe being provided with the usual valve control device *a*, and at *b* I have shown the casing in which the rotor *b* is mounted, said rotor being mounted on and secured to a shaft *b* having a supporting frame shown, or partially

shown at *c*, and on which is mounted and to which is secured a valve casing *d*.

The rotor *b* is provided with pockets *b* which may be of the usual, or any preferred form, and the frame *c* is provided with a head *c* on which the valve casing *d* rests, and said valve casing *d* is cylindrical in form and the bottom thereof is provided with ports or passages *d*, three of which are shown and which communicate with corresponding ports or passages *c* in the head *c* of the frame *c*, and the ports or passages *c* are L-shaped in form, as shown in Fig. 1, and discharge into the pockets *b* of the rotor through tangential discharges *c* in a plate *c* secured in the face of the head *c*, as clearly shown in Figs. 1, 5 and 6.

The steam supply pipe *a* is connected with one end of the valve casing *d* and the opposite end of said valve casing is provided with a stuffing box *d* through which is passed a valve shaft *e* provided at its outer end with a gear *e* which meshes with a vertically arranged rack bar *e*, the lower end of which is provided with a shaft *e* which passes into the cylinder *e* of an ordinary steam pump device and is provided with a piston *e* movable in said cylinder, and the cylinder *e* is provided with the usual valve casing *f* supplied by a pipe *g* which leads to and communicates with the main steam supply pipe at *g*, and the valve casing *f* is also provided with a discharge pipe *g*.

The steam pump device involving the cylinder *e* and its connected parts forms no part of my invention and any suitable device of this class may be employed.

The valve casing *f* is provided with a main steam passage *f* with which the pipe *g* communicates and with supplemental steam passages *f* and *f* which communicate with the cylinder *e*, and said passages *f* and *f* are placed in communication in the usual manner, and said communication is controlled by a valve shaft *h* which passes into the casing *f* and is connected at its outer end with an operating lever *i* having a forked head *i* which operates in connection with a sleeve *i* forming part of a governor *i* mounted on a vertically arranged shaft *i* and provided with a gear *i* which meshes with another gear *i* on the rotor shaft *b*.

The valve shaft *e* which passes into the

valve casing d is provided within said casing and at its inner end with a bearing d^4 , and said shaft is provided at intervals and on its opposite sides with transverse recesses j forming flat web members j^2 on which are mounted radially arranged and radially movable valve devices k , the inner ends of which are forked to receive the web members j^2 , and said devices are provided with springs m which bear on the web members j^2 , and normally serve to force said valve devices outwardly, and the heads or outer ends of the valve devices k are segmental or arc-shaped in form and are of different sizes, as shown in Figs. 8 and 9, and three of which are shown, but any desired number of which may be employed, it being understood that this is also true of the ports or passages d^2 and c^3 which are controlled by the valve devices k , the faces of the valve devices k are provided with pockets k^2 and k^3 , and the valve devices k , or the faces thereof, decrease in dimensions circumferentially from right to left, or in the direction of the steam supply pipe a , and the object of this construction is to control or increase or decrease the supply of steam to the rotor according to conditions under which said rotor is working, and one object of the pockets k^2 and k^3 in the faces of the valve devices k is to reduce friction between said valve devices and the walls of the valve casing d in which they operate.

It will be understood that in the operation of this device, the valve shaft e oscillates only through about a quarter of a revolution and the inner wall of the valve casing d in connection with which the valve devices k operate is provided with grooves n through which the steam is free to pass and through which steam is admitted to the pockets k^2 and k^3 in the valve devices k , and the object of this construction is to reduce the force of the springs m and to cause less friction between the valve devices and the wall or walls of the valve casing d .

In starting the engine the valve devices k are in the position shown in Fig. 8 and the ports or passages d^2 are open, and the steam is admitted directly to the rotor and the operation of the rotor is controlled by the governor i^4 . If the speed of the rotor increases from any cause beyond a predetermined or the desired point, the shaft e is turned so that the valve devices k will gradually cut off the supply of steam and, of course, the increase or decrease of the load under which the engine is working will automatically produce the same result, and in this way the steam supply is automatically controlled under all conditions, and said supply is gradually increased or decreased according to the conditions under which the engine is working, and in this way a uniform operation of the engine is produced under all con-

ditions and without jolt, or jar, the steam supply being gradually and automatically increased, or gradually and automatically decreased according to the load, or other demands placed upon the engine.

It must be borne in mind that the steam is discharged through the ports or passages c^3 into or onto the rotor at different points in its perimeter, and any desired number of the said ports or passages and the valve devices k may be employed and in this way the number of ports or passages discharging into the rotor are regulated, or increased or decreased, according to conditions under which the engines are working, and while in the construction shown the steam ports or passages discharging into the rotor are all arranged at one side thereof this is not necessary and said discharges into the rotor may be so arranged as to extend practically around its perimeter, and while the ports or passages d^2 in the valve casing d are shown as arranged in the same longitudinal line, this arrangement of said ports or passages is also not necessary, and various changes in and modifications of the construction forming a basis of this invention, as herein shown and described, may be made within the scope of the appended claims without departing from the spirit of said invention or sacrificing its advantages.

Having fully described my invention, what I claim as new and desire to secure by Letters Patent, is:—

1. A valve controlling device for steam turbine engines, comprising a cylindrical casing one side of which is provided with a plurality of longitudinally arranged ports or passages, and a valve shaft mounted in said casing and provided with radially arranged and radially movable valve devices adapted to control said ports or passages.

2. A valve controlling device for steam turbine engines, comprising a cylindrical casing one side of which is provided with a plurality of longitudinally arranged ports or passages, and a valve shaft mounted in said casing and provided with radially arranged and radially movable valve devices adapted to control said ports or passages and the bearing surfaces of which are of different circumferential dimensions.

3. A valve controlling device for steam turbine engines, comprising a cylindrical casing provided with a plurality of ports or passages, and a valve shaft mounted in said casing and provided with a plurality of valve devices controlling said ports or passages and whereby said ports or passages may be gradually opened or gradually closed, said valve devices being radially movable and being operated in one direction by springs.

4. A valve controlling device for steam turbines, comprising a cylindrical casing

provided with a plurality of ports or passages, a valve shaft mounted in said casing, automatic means for giving said shaft a rotary oscillating movement, said shaft being 5 reduced at intervals to form webs, and valve devices mounted on and radially movable on said webs and adapted to control said ports or passages.

5. A valve controlling device for steam 10 turbines, comprising a cylindrical casing provided with a plurality of ports or passages, a valve shaft mounted in said casing, automatic means for giving said shaft a rotary oscillating movement, said shaft being

reduced at intervals to form webs, valve devices mounted on and radially movable on said webs and adapted to control said ports or passages, and springs placed in said valve devices and said webs. 15

In testimony that I claim the foregoing as 20 my invention I have signed my name in presence of the subscribing witnesses this 13th day of May 1915.

RICHARD R. DEFFERT.
